UNITED STATES PATENT OFFICE.

THADDEUS FAIRBANKS, OF ST. JOHNSBURY, VERMONT.

IMPROVEMENT IN PLATFORM-SCALES.

Specification forming part of Letters Patent No. 26,485, dated December 20, 1859.

To all whom it may concern:

Be it known that I, THADDEUS FAIRBANKS, of St. Johnsbury, in the county of Caledonia and State of Vermont, have invented a new and useful Improvement in Platform-Scales for Weighing Heavy Bodies; and I do hereby declare that the same is fully described and represented in the following specification and the accompanying drawings, of which—

Figure 1 exhibits a ground plan of a platform-scale provided with my invention, the upper planking of the platform not being shown in such drawings. Fig. 2 is a longitudinal sectional view showing the long multiplying-levers. Fig. 3 is a transverse vertical and central section, while Fig. 4 represents an end view, and Fig. 5 a side elevation, of the platform. Fig. 6 is a side view of the hanging or stirrup link and its rocker-block, to be hereinafter described. Fig. 7 is a transverse section of the two; Fig. 8, an edge view of them, the last three figures being drawn on a scale enlarged relatively to that of the others.

The nature of my invention consists, first, in supporting the fulcrum of the transmitting-lever by the platform or an extension therefrom; also, in the combination of a rocker-block with a stirrup-link and the bearing-pins of the multiplying and transmitting levers; also, in constructing the platform with passages through its end timbers, such being for the reception of the inferior arms of the multiplying-levers and to aid in reducing the depth of the pit required for the scale; also, in providing such platform with loop-passages leading downward from the said lever-arm passages, as hereinafter described, such, also, contributing to a reduction of the depth of the pit.

In the drawings, A represents the weighing-platform, and B its surrounding or pit frame, such platform being supported by means of multiplying-levers C C, depending from the frame B, as shown in Figs. 1, 2, and 4. The inferior arms of the multiplying-levers pass through passages a^3 a^3 , made through the end timbers b^3 b^3 of the platform-frame, such passages being furnished with vertical passages c^3 c^3 , leading out of them, respectively, and through the end timbers. Each of these latter passages is for the reception of the suspen-

sion-link d^3 , by which the platform is hung to the arm of the multiplying-lever. The inner ends of the said multiplying-levers are suspended from a transmitting-lever D, whose knife-edge bearing, or pins a receive the two stirrup-links b b for sustaining the inner ends of the inner arms of the two levers C C. Each of the said stirrup-links, instead of resting directly upon its knife-edge bearing a , is supported upon a rocker-block d , that rests upon the said knife-edge bearing, and has its under surface formed with a curved groove, as shown at e , running transversely with respect to the upper part of the stirrup-link or that which bears upon the block, the groove being curved both longitudinally and transversely. The upper part of the said bearing-block is constructed with an angular recess h , suitably formed to receive the angular bearing i of the cross-bar k of the stirrup-link, the whole being as shown in the drawings. The transmitting-lever D serves, in connection with another lever E, (supported by the frame B, as shown in Fig. 3,) to transmit to the suspension-rod l of the steelyard or weighing-lever the power or pressure of the multiplying-levers C C.

The fulcrum of the lever D is supported directly from the platform A or an extension therefrom, as shown at m in Fig. 3. In other words, the knife-edge bearings of the said lever D rest in ring-bolts projecting from the said platform A.

The advantages obtained by supporting the transmitting-lever from the platform, instead of sustaining its fulcrum or fulera by a standard or other equivalent devices projecting upward from the bottom of the pit in which the platform may be placed, are that by such I am enabled to obtain a very shallow and portable platform-scale and to dispense with the pit-supporting devices of the transmitting-lever, whereby, generally or comparatively speaking, I can employ a pit of less depth. Furthermore, by means of the rocker-bearing of each stirrup-link, the knife-edge bearings of the lever C and that of the stirrup-link are caused to adjust themselves in a vertical line or plane with one another under any movement of the lever, as the rocker-block, in consequence of its rocker or curved form, will enable the upper part of

the stirrup-link to swing into such line or plane passing through the knife-edge bearings of the inner ends of the lever C.

Having thus described my invention, what I claim is—

1. Supporting the fulcrum of a transmitting-lever D by the platform or an extension therefrom, essentially as specified.

2. The combination of the rocker-block with the stirrup-link and the bearing-pins or knife-edges of the connected levers C D, substantially as described.

3. Constructing the platform-frame with the passages a^3 a^3 through each of its end timbers and for the reception of the inferior arms of the multiplying-levers, as described.

4. Providing such platform with loop-passages leading downward out of the lever-passages made in the end timbers, as and for the purpose described.

THADDEUS FAIRBANKS.
